C. H. HILL

DISCONNECTING SWITCH

Filed Dec. 15, 1923

Fig. 2.

Inventor:
Charles H. Hill,
by *Charles S. Smith*,
His Attorney.

UNITED STATES PATENT OFFICE.

CHARLES H. HILL, OF SCHENECTADY, NEW YORK, ASSIGNOR TO GENERAL ELECTRIC COMPANY, A CORPORATION OF NEW YORK.

DISCONNECTING SWITCH.

Application filed December 15, 1923. Serial No. 680,891.

To all whom it may concern:

Be it known that I, CHARLES H. HILL, a citizen of the United States, residing at Schenectady, in the county of Schenectady,

5 State of New York, have invented certain new and useful Improvements in Disconnecting Switches, of which the following is a specification.

10 My invention relates to high tension disconnecting switches suited for outdoor use, and has for its object the provision of means for insuring that the operation of such a switch is not impaired by the accumulation of ice, snow or other material on the switch 15 contacts.

20 In the construction of transmission and distribution systems it is customary, to provide disconnecting switches arranged to disconnect or isolate sections of line, transfer lines, to bypass and isolate transformers, oil switches, lightning arresters and other electrical apparatus for purposes of inspection and repair. These switches when arranged for outdoor use are subject to conditions 25 where sleet, snow or the like accumulates on the contact members blocking or rendering difficult the operation of the switches. Where the system is operated at very high voltages the contact members are further 30 subject to deterioration by reason of corona. In accordance with my invention means are provided for protecting the switch contact both from corona and from accumulations 35 of ice and snow whether the switch be in its open or closed position.

35 My invention will be better understood on reference to the following description when considered in connection with the accompanying drawing and its scope will be 40 pointed out by the appended claims.

45 Referring now to the drawing, Fig. 1 shows a switch in which my invention has been embodied, the switch being illustrated as in closed position; and Fig. 2 is a similar view showing the switch in open position.

The switch comprises contacts 1 and 2 arranged to be moved relatively to one another for the purpose of opening a circuit in conductive relation with the switch leads 3 and 4. The contact 1 is shown as mounted on a stationary insulator 5 and surrounded by a metallic hood 6 in conductive relation therewith. The contact 2 is shown as surrounded

by a metal hood 10 and is supported by a movable insulator 7 mounted on a truck 8 55 which may be moved along the track 9 for the purpose of bringing the contacts 1 and 2 into and out of engagement with each other in a manner disclosed in the patent to Frank P. Lawler No. 1,464,368, August 7, 1923. The hood 10 which surrounds the contact 2 is arranged to envelop the hood 6 in closed position of the switch and is made somewhat larger than the hood 6 in order to insure that an accumulation of ice or snow 65 on the hood 6 will not interfere with the operation of the switch. As indicated in the drawing, the edges of the hoods 6 and 10, as well as other parts subject to high voltage 70 are rounded or made of a form to minimize corona discharge. To this end where the hoods are made of this metal the edges may be spun over small wooden rings if desired.

75 It will be observed that each of the contacts is protected against sleet or snow in the open position of the switch as well as in the closed position. The switch contacts may therefore be opened or closed at any time without trouble from accumulations of sleet or snow.

80 While my invention has been described and illustrated as applied to a switch having one contact arranged to move in a rectilinear direction it is obvious that it has equal utility when both the contacts are arranged to move rectilinearly or when either one or both of the contacts are pivoted to rotate in a substantially horizontal plane into and out of engagement with each other. I accordingly do not wish to be restricted to 85 the particular forms of construction disclosed herein by way of example for the purpose of setting forth my invention in accordance with the patent statutes. The terms of the appended claims are, therefore, 90 not restricted to the precise structure disclosed, but are intended to cover all changes and modifications within the spirit and scope of my invention.

95 What I claim as new and desire to secure 100 by Letters Patent of the United States, is:—

1. A high tension disconnecting switch wherein contacts relatively movable in a horizontal direction are arranged to open and close a circuit, characterized by the fact 105 that each contact is immovably related with

means for protecting it from sleet, snow and the like in both the open and closed positions of said switch.

2. A high tension disconnecting switch wherein contacts relatively movable in a horizontal direction are arranged to open and close a circuit, comprising a shield immoveably fixed to each contact for protecting it from sleet, snow and the like in both the open and closed positions of said switch.

3. A high tension disconnecting switch wherein relatively movable contacts are arranged to open and close a circuit, comprising a member constructed to surround each contact to protect it from sleet, snow and the like and prevent corona discharge, the

member surrounding one of said contacts being arranged to move into the member surrounding another of said contacts.

4. A high tension disconnecting switch 20 wherein relatively movable contacts are arranged to open and close a circuit, comprising a housing member covering each contact to protect it from sleet, snow and the like, the member covering one of said contacts being arranged to move into the member covering another of said contacts upon engagement of said contacts.

In witness whereof, I have hereunto set my hand this 14th day of December, 1923.

CHARLES H. HILL.
